UNITED STATES PATENT OFFICE.

EDWARD B. HAYDEN, OF PLYMOUTH, MASSACHUSETTS.

IMPROVEMENT IN FELTS FOR PAPER MACHINERY.

Specification forming part of Letters Patent No. 222,353, dated December 9, 1879; application filed November 10, 1879.

To all whom it may concern:

Be it known that I, EDWARD B. HAYDEN, of Plymouth, in the county of Plymouth and State of Massachusetts, have invented a new and useful Improvement in Felts for Paper Machinery, of which the following is a specification.

This invention relates to drier-felts (so called) of paper-making machines—that is, the endless band or sheet which travels about the drier-cylinders, and between which band and cylinders the web of paper passes in the act of being dried.

The purpose of my invention is to provide a drier-felt which, while being sufficiently firm and strong to meet all requirements, shall be lighter, more pliable, and more porous—essential qualities in a drier-felt.

My invention consists in a drier-felt composed of a woven fabric the woof of which, or both woof and warp, is formed of rovings, as distinguished from the spun and twisted yarns which are now universally used in fabrics of this character.

The drawing accompanying this specification represents in perspective a portion of a paper-making machine embodying my invention.

In said drawing I have shown a stack of rotary drier-cylinders of a Fourdrinier paper-

machine at A A, &c., as mounted, in the usual manner, in suitable housings B B, while the drier-felt is shown at C as passing about the cylinders A A, also in the usual manner.

In carrying out my invention I weave a web for the drier-felt in which the woof, or both woof and warp, are composed of rovings, in lieu of spun and twisted yarns or threads.

The rovings, as compared with spun and twisted yarns, are porous or loose in texture; hence the web in which they are incorporated is comparatively pliable and porous—qualities which enable it to dry rapidly and render it less liable to break or crack.

I lessen the cost of the product for the reason that I avoid, wholly or in part, the expense of spinning, spooling, and twisting the yarns, which is a matter of considerable moment.

I claim—

A drier-felt, so called, for paper-making machinery, the woof, or both woof and warp, of which is composed of rovings, as distinguished from spun and twisted yarns or threads.

EDWD. B. HAYDEN.
